Primary Examiner — Amber R Stiles

Assistant Examiner — Christen Pilar Brown-Lorrig

(57) **CLAIM**

The ornamental design for a slipper, as shown and described.

DESCRIPTION

FIG. 1 is a top perspective view of a slipper showing my new design.

FIG. 2 is a left side view of a slipper.

FIG. 3 is a right side view of a slipper.

FIG. 4 is a front view of a slipper.

FIG. 5 is a rear view of a slipper.

FIG. 6 is a top view of a slipper.

FIG. 7 is a bottom view of a slipper.

FIG. 8 is a bottom perspective view of a slipper.

FIG. 9 is an enlarged view of an area labeled "9" in FIG. 4; and,

FIG. 10 is an enlarged view of an area labeled "10" in FIG. 5.

The broken lines in FIGS. 4, 5, 9, and 10 are used to annotate an area of enlargement and form no part of the claimed design.

1 Claim, 10 Drawing Sheets
